WASHING MACHINE

Percy E. Barker, Shaker Heights, Ohio

Application April 3, 1935, Serial No. 14,464

38 Claims.

(Cl. 68—132)

My invention particularly relates to washing machines of the agitator type in which the washing operation is performed by forward and backward movements of gyrator vanes which cause washing turbulence in the washing fluid. The invention is particularly applicable to washing machines of the portable type but is also very practicable serviceable for use in stationary laundry trays wherein any compartment will serve as the washing chamber.

Objects of the invention are to provide a gyrator assembly in which all linkage and crank elements are eliminated and which, preferably, is wholly located in the washing tub or chamber. However, essential features of my invention can be embodied in a washing machine in which the motor, gearing, and associated mechanism are located outside of the washing chamber. My gyrator assembly includes the motor and its housing, the gearing and other mechanism necessary to effect the movements and reversals of the gyrator vanes, and the assembly casing, all as one compact unit which can be economically manufactured and assembled, and which, after being assembled, will be hermetically sealed, and in which all moving parts work in oil which is enclosed and protected from pollution by dust and injurious gases.

My improved gyrator assembly cushions the energy that is generally abruptly expended and comparatively slowly recovered in starting and stopping an agitator incident to the periodic reversals of the directions of movement of its vanes.

Other and related objects of my invention will appear from the detailed description of the construction and operation thereof hereinafter given, by reference to the accompanying drawings.

The annexed drawings and the following description set forth in detail certain means embodying my invention, such means constituting, however, but three of the various mechanical forms in which the principle of the invention may be illustrated.

In said annexed drawings: Figure 1 is a central vertical section of a portable type of washing machine embodying my improvements, and in which the entire gyrator assembly is located in the washing chamber, the figure being taken in the plane indicated by the line 1—1, Figure 2;

Figure 2 is a horizontal section, taken in the planes indicated by the line 2—2, Figure 1, one of the extreme positions taken by certain elements, incident to the reversing action, being shown in broken lines;

Figure 3 is a broken horizontal section, taken in the planes indicated by the line 3—3, Figure 1, two extreme positions of certain spring elements and related parts during the reversing actions of the gyrator being shown in broken lines and in dot-and-dash lines, respectively;

Figure 3a is a fragmentary central vertical section, taken in the planes indicated by the line 3a—3a, Figure 3;

Figure 4 is a diagrammatic view illustrating the effect upon certain movable bearings of certain weights eccentrically secured to certain rotating parts of my gyrator assembly, the weights cooperating with certain spring members which alternately assist and oppose the movements of the bearings which are induced by the inertia of the eccentrically mounted rotating weights;

Figure 5 is a fragmentary central vertical section of a form of washing machine embodying my invention in which the agitator actuating mechanism is located in a chamber separate from the washing chamber;

Figure 6 is a central vertical section, partially in elevation, of a form of my invention applied to a compartment of a standard laundry tray;

Figure 7 is a plan view of the gyrator assembly shown in Figure 6; and

Figure 8 is a plan view of two compartments of a laundry tray in one of which is mounted my improved gyrator assembly, certain extreme positions assumed by the assembly during the reversing actions being indicated in broken lines.

Referring to the annexed drawings in which the same parts are indicated by the same respective numbers in the several views, and particularly referring to Figures 1, 2, 3, 3a, and 4, a tub 1, which may be any suitable vessel of practicable size and material, serves as a washing chamber, and is provided with a close fitting cover 2 having an exterior central knob portion 3 forming a support for an upper bearing 33. The tub 1 is provided with handles 62. Within this tub, I position my improved gyrator assembly 36 which is adapted to turn in the upper bearing 33 and in a lower opposed bearing 23' upwardly extended from a base plate 23 secured to the inner wall of the bottom of the tub 1. A plate 22 is secured to the bottom of the gyrator casing and is formed with a downwardly-extended trunnion 22' which is journaled in the bearing 23'. The gyrator assembly includes an enclosed outer casing comprised of a saucer-shaped base member 12 upon which is erected an upper member 5 which converges inwardly and upwardly and at its upper central portion merges into a tube 32 extended

upwardly through a sleeve 34 which is journalled in the upper bearing 33. The tube 32 is provided with an electric socket (not shown) which is adapted to removably accommodate a plug 34' in which are secured electric conductors 31'. Downwardly extended through the tube 32 and through a plug 35 tightly fitted within the tube 32 and disposed adjacent the bottom of the tube are electric conductors 31 running to a motor 4, the motor being of suitable R. P. M. to effect, through the speed reduction gearing used, to and fro movements of the gyrator vanes at a washing frequency, which frequency, as is well known, is comparatively low as compared with a vibrating frequency. The conductors 31 above the plug 35 and within the tube 32 are enclosed by an air-tight sleeve 63 of sealing wax. Mounted upon the upper casing member 5 and exteriorly of the tube 32 and tightly fitted to the latter is an elongated hub 37 to which are secured the inner edges of a plurality of spaced agitator vanes 37'.

The motor 4 is formed with and secured to a cover member 11 and a base member 27, from the center of the latter of which a boss 28 extends upwardly and forms a bearing for a downwardly-extended motor shaft 38. The motor base member 27 is formed with outwardly-extended diametrically-opposed portions 29 having downwardly-extended tubular bosses 29' within which pins 9 and 10 are dependably secured. These pins 9 and 10 are enclosed in bushings 30 which form journals for a pair of elongated hubs 7' and 8' secured respectively to horizontally-spaced gears 7 and 8 which engage at their inner adjacent edge portions with the opposite sides of a pinion 6 secured to the lower end of the motor shaft 38. The bodies of these gears 7 and 8 are formed with a plurality of spaced openings 7' and 8' in order to reduce their weight. The motor base member 27 is also formed with diametrically-opposed ears 45, Figure 2, spaced ninety degrees from the bosses 29' and forming supports for downwardly extending pins 46 which bear upon the casing member 12 and assist in supporting the motor 4.

The motor and gearing are secured to the casing comprised of the members 12, 5, and 32 by means of pins 20 and 21 secured in and downwardly extended from the pins 9 and 10, respectively, and passing through the casing member 12. These pins 20 and 21 also secure to the lower surface of the casing member 12 an inverted saucer-shaped plate 19. Projecting downwardly from, and secured to, the plate 19 are a pair of diametrically opposed lugs 41 and 42, Figures 3 and 3a, whose function will be later described.

From the foregoing description and the accompanying drawings, it is evident that the axes of the bearing pins 9 and 10 for the gears 7 and 8 are not fixed but, if means are provided for swinging them to and fro in arcs having centers concentric with the axis of the motor shaft 38, they are free so to swing, and that such swinging movements will be communicated to the gyrator assembly including the casing 12, 5 and 32, and vanes, the motor, and the plate 19. I shall now describe means for effecting such swinging movements.

Secured to the gears 7 and 8, and adjacent the peripheries thereof, and to symmetrically disposed portions thereof, are weights 15-16-17-18, the weights being in opposed pairs 15-16 and 17-18, respectively, fastened to the top and bottom faces of the gears 7 and 8 by rivets 49. When the gears 7 and 8 are rotated from a starting position such

as illustrated, for instance, by the full line showing thereof in Figures 2 and 4, and the motor shaft 38 turns in a counter-clockwise direction, the gears 7 and 8 turn in a clockwise direction, and the weights 15-16-17-18 move toward the positions shown therefor in dot-and-dash lines in Figure 4, the tangentially-directed forces created by the weights tending to move the axes of the bearing pins 9 and 10 in arcs having the axis of the motor shaft 38 as a center and in clockwise direction, Figures 2 and 4. This tendency of the pins 9 and 10 so to be moved continues until the rotation of the gears 7 and 8 has carried the weights through a sufficient arc to reverse the direction in which the centrifugal force created by the weights tend to move the axes of the pins 9 and 10. Then, until the continued rotation of the gears 7 and 8 has again reversed the direction of the throw induced by the inertia of the weights, the weights 15-16-17-18 and the gears 7 and 8 move toward the positions shown therefor in broken lines, Figure 4, and the axes of the pins 9 and 10 move in the arcs in a counter-clockwise direction. These cycles are periodically repeated by the continued rotation of the gears 7 and 8, and the axes of the pins 9 and 10 move back and forth in the paths of the two arcs shown in Figure 4 and, consequently, the whole gyrator assembly 36, including the vanes 37', will have to and fro oscillating movements.

I provide means for intensifying the strokes of the vanes 37' in an assembly such as thus far described, and for cushioning or equalizing the energy that would be expended in such an assembly in stopping the pins 9 and 10 and the related elements in one direction of movement and in starting the movement of these pins and elements in the other direction. These means will now be described.

Journalled upon the upwardly-extended bearing 23' of the base plate 23 is an inner spring block 24 between and to which and outer spring blocks 24' are secured by means of rivets 40 two leaf spring assemblies 25 and 26. The lugs 41 and 42 which have been mentioned as extended downwardly from the plate 19 extend downwardly slightly further than the springs 25 and 26 and are disposed between the latter adjacent their ends so that the springs 25 and 26 will intercept these lugs 41 and 42 when the plate 19 is turned incident to the reciprocatory movements of the gyrator assembly. The lugs 41 and 42 are of a horizontal length slightly less than the distance between the opposed inner leaves of the springs 25 and 26, as clearly indicated in Figure 3 by the space "60". There are other lugs 43 and 44, a pair of them and diametrically opposed, projected upwardly from the stationary base member 23, and lying, normally, adjacently interiorly of the movable lugs 41 and 42. These fixed lugs 43 and 44 are disposed between the opposed springs 25 and 26 so as also to contact with the inner long leaves of the springs 25 and 26, after a slight movement of the latter from their normal positions, the amount of such movement being represented by the space 60', Figure 3.

From the foregoing, it is evident that the reciprocatory movements of the gyrator assembly will cause the lug 41 to engage and move an end of one spring 25, and the lug 42 to engage and move an end of the other spring 26, both spring movements being clockwise, if the direction of movement of the gearing is such as indicated by the dot-and-dash showing in Figure 4. However, the opposite ends of the respective springs can-

not move clockwise, as is true of the ends first-mentioned, but are stopped and bent into symmetrically opposite positions, to those assumed by the first-mentioned spring ends, by the fixed lugs 44 and 43. The result is indicated in the dot-and-dash showing of Figure 3. If the gyrator assembly had been moved in the opposite direction to that just described, i. e., to the positions shown in broken lines in Figures 2 and 4, then 10 the effect upon the springs 25 and 26 and the positions assumed by the latter would be those indicated in the broken line showings of Figure 3.

The operation of the aforementioned elements, and the effect upon the reversing of directions of 15 movement of the vanes 37', are as follows:

When the gyrator assembly tends to move in counter-clockwise direction, for instance, Figure 4, the springs 25 and 26 are increasingly tensioned toward the position illustrated by the broken line 20 showing of Figure 3, this tensioning of the springs continuing until the reactive forces of the springs 25 and 26 are equal to the tangentially-directed forces of the weights 15-16-17-18, by which time the rotation of the gears 7 and 8 has carried 25 the weights to approximately the broken line positions shown in Figures 2 and 4. Then there is a dwell or rest period in the movement of the gyrator assembly in its reciprocatory path until the tangentially-directed forces of the weights 30 15-16-17-18 tends to reverse the direction of movement of the gyrator assembly. During this dwell period the gears 7 and 8 continue to rotate and the tangentially-directed forces of the weights 35 15-16-17-18 are reversed in direction. As soon as these tangentially-directed forces tend to move the gyrator assembly in a direction the same as that in which the reactive forces of the tensioned springs 25 and 26 tend to move the 40 gyrator assembly, then the weights and springs 45 aggregate their impulses and snap the gyrator assembly toward the opposite end of its reciprocatory path of movement, or tend to so snap it. This induced snap action of the gyrator assembly is through an arc of about 90°, when the cycle has been repeated often enough to have built up the 50 full accumulative effect of the springs 25 and 26. Thus, the action of the springs 25 and 26 not only gives the gyrator assembly a snap action and increases its speed of reciprocatory movement at the beginning of its stroke in one direction, but also slows up its movement at the end of the stroke in each direction and thus cushions or 55 equalizes the energy which is expended in stopping the movement of the gyrator assembly in one direction and in starting its movement in the opposite direction, when the weights rotate by the centers which define the changes of direction in which the tangentially-directed forces are exerted. This cushioning and smoothing out of energy application is occasioned, of course, by the resistance of the springs 25 and 26 to compression and by the reactive stresses exerted by the springs when they are freed from the forces 60 tending to compress them.

65 I provide means for lubricating moving parts and enclose the same so that there is no contamination by dust and injurious liquids and gases. These means comprise open bottom cups or shells 13 and 14 downwardly extended from the main 70 bodies of the gears 7 and 8 and spaced somewhat from the bottom ends of the bushings 30 so as to form oil cups from which by means of openings 41 in the bushings 30 and hubs 7' and 8' therefor the lubricant finds entrance to the moving surfaces, there being provided a felt and

wick arrangement 48 for effecting the transfer of the lubricant. The lubricant is splashed up into the cups 13 and 14 by their movement with the gears 7 and 8 from an oil well 39 which is formed in the bottom of the casing member 12 5 and is filled to about the height of the bottom of the cups 13 and 14. The lubricant also travels upwardly and outwardly along the conical sides of the cups 13 and 14 due to the rotation of the gears 7 and 8. 10

In Figure 5, I disclose a form of my invention in which the motor gearing, and related mechanism are disposed in the space 65 located exteriorly of and beneath the washing chamber of the tub 64 and between the legs 66 upon which the tub is 15 supported. A casing 67 for the operating mechanism is formed with an elongated standard 68 which extends upwardly into the washing chamber of the tub 64 and is connected to an agitator of any desired style provided with vanes 69. The standard 68 is supported by and turns in an elongated bearing 70 mounted upon the inside face of the bottom of the washing chamber of the tub 64. 20

Referring particularly to Figures 6, 7, and 8, I 25 therein disclose an adaptation of my invention to a compartment of a standard laundry tray, in which "50" represents such compartment of a standard tub assembly which is supplied with hot and cold water through the pipes 51. For supporting my improved gyrator assembly 36' in such 30 a tray compartment 50, I provide an upper cross bar 52 adapted to be tightly secured to the top of the compartment 50 by means of clamps 53. This bar 52 has an elongated downwardly-extended 35 boss 54 interiorly of which and adjacent the bottom of which is mounted a cylindrical journal member 55 forming the top of the gyrator assembly 36'. Secured to the top of the journal member 55 is a tube 56 which extends upwardly through the bar 52 and forms a conduit for conductors 57 leading to the motor 4. Extending upwardly from the casing member 5 is a central vane support 61 to which are attached a plurality of outwardly extended spaced vanes 37'. The journal member 55 projects upwardly from this 40 vane support 61. Surrounding the conductor tube 56 is a coiled spring 59 secured at its upper end in the stationary member 52 and at its lower end in the journal member 55. The upper end of the tube 56 is exteriorly threaded and engaged 45 by a nut 58 whereby the whole assembly can be locked in position, the nut 58 being adapted to turn freely and smoothly upon the portion of the upper surface of the bar 52 with which it contacts. Such turning is caused by the turning of the tube 56 and the journal member 55 in the 50 boss 54, and the turning of the vanes 37', and the motor 4, and the entire gyrator assembly, by means within the casing members 5 and 12 substantially identical with those described with reference to Figures 1, 2, 3, and 3a, except that the 55 fixed base 23, the leaf springs 25 and 26, the cup-shaped member 19, and the related mechanism beneath the member 19, which are described and shown with reference to the form of invention shown in Figures 1, 2, 3, and 3a, are dispensed with in the form of invention shown in Figures 6, 7, and 8, and the effect of the springs 25 and 26 upon the swinging movements of the bearings 9 and 10 described with reference to Figures 1, 2, 3, 60 and 3a, is accomplished in the form of invention shown in Figures 5, 6, and 7, by the spring 59. Also, in this form of the invention, the casing members 5 and 12 are secured together by countersunk screws 62, Figure 7. It is evident that 65

70 75

the arcuate movement of the axes of the pins 9 and 10, under the action of the weights 15—16—17—18, will put the spring 59 under tension which will effect alternately a cushioning for, 5 and a snapping of, the strokes of the vanes 36'.

The form of invention shown in Figures 6, 7, 10 and 8, differs in one particular, in effect, from that shown in Figures 1, 2, 3, 3a, and 4, in that the spring 59 commences immediately to be put 15 under tension, upon any movement of the gyrator assembly; whereas, there is some slight movement of the gyrator assembly, before the springs 25 and 26 are so acted upon, in the construction shown in Figures 1, 2, 3, 3a and 4, because of the 20 provision of the slight spaces 60 and 60', Figure 3, between the lugs 41, 42, 43, and 44, and the adjacent leaves of the springs 25 and 26.

What I claim is:

1. A gyrator assembly for a washing machine 20 consisting of an entirely sealed casing, agitator vanes suitable for effecting washing turbulence carried by said casing to move therewith, a motor and a reciprocable inertia mass carried in said casing, said motor being operatively connected 25 to said mass so as to reciprocate the latter, said mass being operatively connected to the casing so as to effect reciprocatory movements of the latter and of the vanes when the mass is reciprocated by the motor, and the motor and its 30 connections with the inertia mass, and the connections of the latter with the casing, being such as to effect the reciprocating movements of the casing and vanes at a washing frequency.

2. A gyrator assembly for a washing machine 35 consisting of an entirely sealed casing, agitator vanes suitable for effecting washing turbulence carried by said casing to move therewith, an electric motor and a shaft driven thereby, and a reciprocable inertia mass, said motor and shaft and inertia mass being carried in the casing, said driven shaft being operatively connected to said mass so as to reciprocate the same, said mass being operatively connected to the casing so as to effect reciprocatory movements of the latter 40 and of the vanes when the mass is reciprocated by the shaft, and the motor and its connections with the inertia mass, and the connections of the latter with the casing, being such as to effect the reciprocatory movements of the casing and the vanes at a washing frequency.

3. A gyrator assembly for a washing machine 50 consisting of an entirely sealed casing, agitator vanes suitable for effecting washing turbulence carried by said casing to move therewith, a motor and a reciprocable inertia mass carried in said casing, said motor being operatively connected to said mass so as to reciprocate the latter, said mass being operatively connected to the casing so as to effect reciprocatory movements of the latter and of the vanes when the mass is reciprocated by the motor, and the motor and its 55 connections with the inertia mass, and the connections of the latter with the casing, being such as to effect the reciprocatory movements of the casing and vanes at a washing frequency, and means alternately opposing and assisting the actions of said mass and thus regulating the character of the reciprocatory movements of the casing and vanes.

4. A gyrator assembly for a washing machine 60 consisting of an entirely sealed casing, agitator vanes suitable for effecting washing turbulence carried by said casing to move therewith, a motor and a reciprocable inertia mass carried in said casing, said motor being operatively con-

nected to said mass so as to reciprocate the latter, said mass being operatively connected to the casing so as to effect reciprocatory movements of the latter and of the vanes when the mass is reciprocated by the motor, and the motor and its connections with the inertia mass, and the connections of the latter with the casing, being such as to effect the reciprocatory movements of the casing and vanes at a washing frequency, and resilient means alternately opposing and assisting the actions of said mass to slow up the movement of the casing and vanes during a portion of their stroke in each direction and to speed up said movement during the balance of the stroke.

5. A gyrator assembly consisting of an entirely sealed casing, agitator vanes carried by said casing to move therewith, an electric motor having a driven shaft, a pinion secured to the shaft, a pair of speed-reduction gears symmetrically arranged about the axis of the shaft, and bearing pins which are carried by said casing and upon which the gears are respectively mounted, said gears having symmetrically arranged eccentric inertia masses, said motor, 25 shaft, gears and inertia masses being carried in said casing, and said pinion engaging the gears, thus to effect movements of the gears in an oscillatory path of movement, and hence, also of the casing and vanes.

6. A washing machine comprising a tub forming a washing chamber, a gyrator assembly, and means for journalling the assembly in the tub, said gyrator consisting of spaced gyrator vanes positioned in the washing chamber and suitable 30 for effecting washing turbulence and of a self-contained oscillatory unit comprising an entirely sealed casing to which said vanes are secured and with which the vanes move, bearing pins carried by the casing, a motor having a driven 35 shaft, rotatable members carried by said bearing pins and operatively connected to the motor shaft so as to be rotated thereby at an angular speed different than that of said motor shaft, and unbalanced inertia masses secured to the 40 respective rotatable members, the motor, motor shaft, rotatable members, inertia masses and bearing pins being carried in the casing, and the motor, the rotatable members, and the connection of the motor shaft with the rotatable members, being such as to effect the oscillatory movements of the casing and the vanes at a washing 45 frequency.

7. A washing machine comprising a tub forming a washing chamber, a gyrator assembly, and means for journalling the assembly in the tub, said gyrator assembly consisting of spaced gyrator vanes positioned in the washing chamber and suitable for effecting washing turbulence and of a self-contained oscillatory unit comprising an entirely sealed casing to which said vanes are secured and with which the vanes move, a motor having a driven shaft, gears symmetrically arranged about the axis of the motor shaft and having parallel axes offset therefrom and upon which they are rotatable, said gears being carried by the casing and being operatively connected to the motor shaft so as to be rotated thereby, and unbalanced inertia masses 55 secured to the respective gears, the motor, motor shaft, gears and inertia masses being carried in the casing, and the motor, the gears, and the connection of the motor shaft with the gears, being such as to effect the oscillatory 60 movements of the casing and the vanes at a washing frequency.

movements of the casing and the vanes at a washing frequency.

8. A washing machine comprising a tub forming a washing chamber and provided with opposed bearings, and a gyrator assembly disposed in the washing chamber, journalled in the bearings, and consisting of spaced agitator vanes and of a self-contained oscillatory unit comprising an entirely sealed casing to which the vanes are connected to be operatively controlled by the movements of the casing, a motor having a driven shaft, a housing for the motor carried in the casing, a pair of opposed gears disposed upon opposite sides of the motor shaft and symmetrically arranged relative thereto, the gears being operatively connected to the motor shaft so as to be rotated thereby, bearing pins secured to the motor housing and upon which the gears rotate, the bearing pins being also secured to the casing, and the gears, bearing pins and gear connections being carried in the casing, and inertia masses eccentrically secured to the gears, thus causing the tangentially-directed forces created by the rotation of the gears to pull the bearing pins alternately in opposite directions in arcs of a circle having its center in the axis of the motor shaft to effect the oscillatory movements of said self-contained unit.

9. A washing machine comprising a tub forming a washing chamber and provided with opposed bearings; a gyratory assembly disposed in the washing chamber, journalled in the bearings, and consisting of spaced agitator vanes and of a self-contained oscillatory unit comprising an entirely sealed casing to which the vanes are connected to be operatively controlled by the movements of the casing, a motor having a driven shaft, a housing for the motor carried in the casing, a pair of gears disposed upon opposite sides of the motor shaft and symmetrically arranged relative thereto, the gears being operatively connected to the motor shaft so as to be rotated thereby, bearing pins which are secured to the motor housing and to the casing and upon which the gears rotate, the gears, bearing pins and gear connections being carried in the casing, and inertia masses eccentrically secured to the gears, thus causing the tangentially-directed forces created by the rotation of the gears to pull the bearing pins alternately in opposite directions in arcs of a circle having its center in the axis of the motor shaft to effect the oscillatory movements of said self-contained unit; and a plurality of leaf springs associated with the tub and the self-contained oscillatory unit so as alternately to oppose and to assist the movements of the latter.

10. A washing machine comprising a tub having a washing chamber, and a gyratory assembly journalled within the tub and having spaced agitator vanes positioned in the washing chamber, an entirely sealed casing to the exterior surface of which the vanes are secured, a pair of parallel bearing pins secured to and carried in the casing, a pair of gears relatively spaced edgewise and mounted to rotate on the respective bearing pins, a motor housing secured to the bearing pins and carried in the casing, a motor secured to and in the motor housing and having a driven shaft extended outwardly from the housing, a pinion secured to the shaft and disposed in the space between said pair of gears and engaging both of the latter, and symmetrically arranged inertia masses eccentrically secured to the gears.

11. A washing machine comprising a tub having a washing chamber, an upstanding bearing

member secured to the inner face of the bottom of the tub, and an opposed bearing carried by the tub adjacent the top of the latter; a gyratory assembly journalled in said bearings and having spaced agitator vanes positioned in the washing chamber, an entirely sealed casing to the exterior surface of which the vanes are secured, a pair of parallel vertical bearing pins secured to and carried in the casing, a pair of edgewise-spaced and horizontally-aligned gears mounted to rotate on the respective bearing pins, a motor housing secured to the bearing pins and carried in the casing, a motor secured to and in the motor housing and having a depending driven shaft extended outwardly from the housing, a pinion secured to the shaft and disposed in the space between said pair of gears and engaging both of the latter, and symmetrically arranged inertia masses eccentrically secured to the gears; a pair of oppositely-disposed leaf springs mounted upon opposite sides of said lower tub bearing; lugs secured to the tub bottom and upstanding therefrom and disposed between said springs and adjacent the ends thereof; and other lugs secured to and depending from the casing between said springs and adjacent the ends thereof.

12. A gyrator assembly mounted on a support for gyratory movement relative thereto and comprising a movable casing, a motor having component fixed to said casing and a second component rotatable with respect to the first-mentioned component, an unbalanced inertia mass rotatably carried by said first-mentioned component, a driving connection between said unbalanced mass and said second component, and agitating means carried by the casing and rendered effective by the movements of the latter, the gyrator assembly being so mounted on said support and said unbalanced inertia mass being so associated with said agitating means that controlled gyratory movement of said agitating means is effected.

13. In combination, a support having a bearing, and a gyrator assembly comprising a casing rotatably carried by said bearing, a motor having one component fixed to the casing and a second component rotatable with respect to said one component, an unbalanced inertia mass rotatably carried by said one component, a driving connection between said unbalanced mass and said second component, and agitating vanes carried by the casing and rendered effective by the movements of the latter.

14. A gyrator assembly comprising a casing, a motor having a rotatable component, a wheel mounted on the casing for rotation about an axis eccentric with respect to the axis of said rotatable component, a driving connection between said rotatable component and said wheel, an inertia mass carried by said wheel in unbalanced position, all such that oscillatory movements are imparted to said casing by the rotation of the wheel, and agitating means carried by the casing and rendered effective by the oscillatory movements of the latter.

15. A gyrator assembly comprising a motor having a component which is rotatable with respect to a second component, wheels carried by said second component and rotatable relative to the latter, driving connections between said wheels and the rotatable component, inertia masses mounted on said wheels and respectively disposed in unbalanced positions, said wheels and said masses being so disposed with respect to the axis of the rotatable motor component that the

actions of said masses are cumulative and cause oscillation of said second component, and agitating means associated with said second component and actuated by the oscillation of the latter.

5 16. A gyrator assembly comprising a motor having two components one of which is rotatable with respect to the other, a wheel rotatably mounted on said other component and peripherally engaging said one component, an inertia mass fixed to said wheel in unbalanced position and rotatable therewith, all such that rotation of the rotatable motor component causes oscillation of the other motor component, and agitating means associated with said other component and actuated by the oscillations of the latter.

10 17. A gyrator assembly comprising an electric motor having a rotor and a stator, a pinion fixed to the rotor, a gear wheel rotatably mounted on the stator and peripherally engaging said pinion, an inertia mass fixed to said wheel in unbalanced position and rotatable therewith, all such that rotation of the rotor causes oscillation of the stator, and agitating means associated with the stator and rendered effective by the oscillations of the latter.

15 18. A gyrator assembly comprising a casing, a motor sealed within the casing and having two components which are rotatable relative to one another, a pinion fixed to one of said components, a gear wheel rotatably mounted on the other of said components and peripherally engaging said pinion, said casing being secured to said other component, an inertia mass fixed to said wheel in unbalanced position and rotatable therewith, all such that rotation of said one motor component causes oscillation of said casing, and vanes carried by the casing.

20 19. In combination, a support; a gyrator assembly rotatably carried by the support and comprising a motor having two components each rotatable with respect to the other, an unbalanced inertia mass rotatably mounted on one of said components, agitating means carried by said one component and rendered effective by the movements of the latter, and a driving connection between said unbalanced mass and the second of said components, all such that operation of said motor causes gyration of said gyratory assembly relative to said support; and means effective between the gyrator assembly and said support alternately to dampen and to intensify the gyratory movements of the gyrator assembly.

25 20. In combination, a support; a gyrator assembly comprising a casing rotatably carried by the support, vanes on the exterior surface of the casing, a motor having a component fixed to the casing and a second component rotatable with respect to the first-mentioned component, an unbalanced inertia mass rotatably mounted on the first-mentioned component, and a driving connection between said unbalanced mass and said second component, all such that operation of said motor causes oscillation of said casing and vanes relative to said support; and resilient means effective between said casing and said support alternately to dampen and to intensify the oscillatory movements of the casing.

30 21. In combination, a support a gyrator assembly comprising a casing rotatably carried by the support, vanes carried by the casing and rendered effective by the movements of the latter, an electric motor having a stator fixed to the casing and a rotor, a pinion carried by the rotor, gear wheels rotatably mounted on the casing, said gear wheels being oppositely disposed with re-

spect to said pinion and having driving engagement therewith, and an inertia mass carried by each gear wheel and so disposed in unbalanced position that the actions of the inertia masses are cumulative and cause oscillation of said casing relative to said support; and resilient means effective between said casing and said support to intensify the intermediate part of each unidirectional movement of the casing and to dampen the final part of each such movement.

35 22. A gyrator assembly comprising a casing, vanes on the exterior surface of the casing, a motor, oscillatory inertia masses located symmetrically about the motor axis, said motor and said masses being carried in and connected to the casing to move therewith, and means operatively connecting said masses to the motor to oscillate the masses by the motor, and hence to oscillate the motor and the casing, the casing, motor and masses having fixed axes of gyration.

40 23. A gyrator assembly comprising a movable casing, a motor having a component fixed to said casing and a second component rotatable with respect to the first-mentioned component, an unbalanced inertia mass mounted on said first-mentioned component, a driving connection between said unbalanced mass and said second component, the gyrator assembly being so mounted and the mounting of said mass being such as to effect to and fro movements of said first-mentioned component, and hence of said casing, in a common path of movement when said mass is driven by the motor, and agitating means associated with said casing and actuated by the to and fro movements of the latter.

45 24. A gyrator assembly comprising a motor having two movable components which are relatively rotatable, an unbalanced inertia mass rotatably mounted on one of said components, driving connections between the other of said components and said unbalanced mass to rotate the latter, the gyrator assembly being so mounted and the mounting of said unbalanced mass being such as to effect by its rotation to and fro movements of said one component in a common path of movement, and agitating means associated with said one component and actuated by said to and fro movements of the latter.

50 25. A gyrator assembly comprising a movable casing, an unbalanced inertia mass mounted on said casing for movement with said casing and also for movement relative thereto, means for moving said unbalanced mass relative to said casing, the gyrator assembly being so mounted and the mounting of said unbalanced mass being such that movement thereof relative to said casing by said means effects to and fro movements of said casing in a common path of movement, and agitating means associated with said casing and actuated by said to and fro movements of the latter.

55 26. A gyrator assembly comprising a symmetrically formed casing, a motor carried in said casing and having a rotatable component, an unbalanced inertia mass relatively rotatably secured to said casing for rotation about an axis eccentric with respect to the axis of symmetry of said casing, driving connections between said rotatable component and said unbalanced mass to rotate the latter, all such that said casing is oscillated when said unbalanced mass is rotated about said eccentric axis, and agitating means carried by said casing and rendered effective by the oscillations of the latter.

60 27. In combination, a support and a gyrator

assembly comprising a motor carried by said support so as to permit movement of said motor relative to said support, said motor having two components which are rotatable relative to one another, 5 an unbalanced inertia mass mounted on one of said components for rotation about an axis eccentric with respect to the motor axis, driving connections between the other of said components and said unbalanced mass to rotate the latter, and 10 agitating means associated with said one component, all such that said agitating means are rendered effective when said motor is operated.

28. A gyrator assembly comprising a motor having two movable components which are relatively rotatable, an unbalanced inertia mass rotatably carried by one of said components, the axis of rotation of said unbalanced mass being eccentric to the motor axis, driving connections between said unbalanced mass and the other of 20 said components to rotate said unbalanced mass about said eccentric axis, and agitating means associated with said one component and actuated by the movements of said unbalanced mass.

29. A gyrator assembly comprising a movable 25 casing, a power driven rotor, an unbalanced inertia mass carried by said casing and rotatable relative thereto about an axis eccentric with respect to the rotor axis, driving connections between said rotor and said unbalanced mass to 30 rotate the latter, and agitating means associated with said casing, all such that rotation of said unbalanced mass effects movement of said casing and renders said means effective.

30. A gyrator assembly comprising a casing, an 35 unbalanced inertia mass carried by said casing and rotatable relative thereto, means carried by said casing for rotating said unbalanced mass relative to said casing, the gyrator assembly being so mounted and the mounting of said unbalanced 40 mass being such as to effect to and fro movements of said casing in a common path of movement when said unbalanced mass is rotated relative to said casing, and agitating means associated with said casing in such manner as to be rendered 45 effective by said to and fro movements of the latter.

31. A gyrator assembly comprising a symmetrically formed casing, an unbalanced inertia mass carried by said casing and rotatable relative thereto about an axis eccentric with respect to the axis of symmetry of said casing, means for rotating said unbalanced mass about said eccentric axis, and agitating means associated with said casing in such manner as to be rendered 55 effective by the rotation of said unbalanced mass about said eccentric axis.

32. A gyrator assembly mounted on a support for movement about an axis of gyration and comprising agitating means, an unbalanced 60 inertia mass mounted for rotation about an axis eccentric with respect to said axis of gyration and associated with said agitating means in such manner that rotation of said unbalanced mass about said eccentric axis effects oscillatory movements of said agitating means, and means for 65 rotating said unbalanced mass about said eccentric axis.

33. A gyrator assembly mounted on a support for movement about an axis of gyration and comprising agitating means, a bearing element fixedly connected with said agitating means and having an axis eccentric with respect to said axis of gyration, an unbalanced inertia mass carried by said bearing element for rotation about said eccentric axis, and means for rotating said unbalanced mass about said eccentric axis.

34. In combination, the gyrator assembly set 10 forth in claim 32 and means to dampen and to intensify the oscillatory movements of the agitating means.

35. In combination, a gyrator assembly having an axis of gyration and comprising agitating 15 means, an unbalanced inertia mass mounted for rotation about an axis eccentric with respect to said axis of gyration and associated with said agitating means in such manner that rotation of said unbalanced mass about said eccentric 20 axis effects oscillatory movements of said agitating means, and means for rotating said unbalanced mass about said eccentric axis; and means to dampen and to intensify said oscillatory movements of said agitating means, the last-mentioned means being constructed and associated 25 with said gyrator assembly in such manner that, on starting operation of said gyrator assembly, said last-mentioned means become operative somewhat subsequent to the commencement of 30 the oscillatory movements of said agitating means.

36. A gyrator assembly comprising agitating means, an unbalanced inertia mass, the gyrator assembly being so mounted and said unbalanced 35 inertia mass being relatively rotatably secured to said agitating means in such manner that rotation of said unbalanced mass relative to said agitating means effects to and fro movements of said agitating means in a common path, and 40 means for rotating said unbalanced mass relative to said agitating means thereby to move said agitating means to and fro in a common path.

37. In combination, the gyrator assembly set 45 forth in claim 36 and means to dampen and to intensify the to and fro movements of the agitating means.

38. In combination, a gyrator assembly comprising agitating means, an unbalanced inertia mass, the gyrator assembly being so mounted 50 and said unbalanced inertia mass being relatively rotatably secured to said agitating means in such manner that rotation of said unbalanced mass effects to and fro movements of said agitating means in a common path, and means for rotating 55 said unbalanced mass relative to said agitating means; and means to dampen and to intensify said to and fro movements of said agitating means, the last-mentioned means being constructed and associated with said gyrator assembly in such manner that, on starting operation 60 of said gyrator assembly, said last-mentioned means become operative somewhat subsequent to the commencement of the to and fro movements of said agitating means.

PERCY E. BARKER.
